(57) **CLAIM**

The ornamental design for a lip gloss tube, as shown and described.

DESCRIPTION

FIG. 1 is a top perspective view of a lip gloss tube, showing my new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a section view thereof taken about line 8-8 in FIG. 6;

FIG. 9 is a top perspective view thereof; and,

FIG. 10 is a top perspective view thereof, showing an exploded view of example environmental structure in broken lines.

The broken lines form no part of the claimed design.
